DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series, and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

MULTI-LEVEL COMPRESSED INDEX INSERTION AND DELETION METHOD AND MEANS

Edward Loizides, Poughkeepsie, and George F. Steigerwalt, Jr., Hyde Park, N.Y., assignors to International Business Machines Corporation, Armonk, N.Y.

Continuation of application Ser. No. 417,459, Nov. 19, 1973, which is a continuation of application Ser. No. 99,863, Dec. 21, 1970. This application Apr. 24, 1975, Ser. No. 573,494

Int. Cl. G06F 7/00

U.S. Cl. 444—1

34 Sheets Drawing. 111 Pages Specification

To enable the maintenance on a real-time basis of a multi-level compressed index generated by the method and means disclosed in U.S. Pat. 3,603,937 issued Sept. 7, 1971. Such index can be searched by the method and means disclosed in U.S. Pat. 3,643,226 issued Feb. 15, 1972. Two types of operation on an existing multi-level compressed index structure are disclosed; they are (1) insertion of new compressed key entries, and (2) deletion of existing compressed key entries. Both operations (1) and (2) begin at the lowest index level and proceed upward through the multi-level compressed index hierarchy until the operations are complete.
